(57) **CLAIM**

The ornamental design for a remote control, substantially as shown and described.

DESCRIPTION

FIG. 1 is a perspective view of a remote control showing our design;

FIG. 2 is a top plan view thereof;

FIG. 3 is a right side elevation view thereof;

FIG. 4 is a bottom plan view thereof;

FIG. 5 is a left side elevation view thereof;

FIG. 6 is a front elevation view thereof; and,

FIG. 7 is a rear elevation view thereof.

The broken lines immediately adjacent to the claimed areas in the views represent the boundaries of the claimed design. Other broken lines showing an environment are for illustrative purposes only. None of the broken lines or areas within them form part of the claimed design.
